CLOSURE ACTUATING AND LOCKING
MECHANISM

Charles E. Arthur, Napa, Calif.

Application March 18, 1939, Serial No. 262,768

12 Claims. (Cl. 292—48)

The invention relates to mechanisms for closing and locking doors and principally to such mechanisms as are used on closures for openings exposed to weather or to an artificially maintained pressure, such as is the case on various ship doors and closures and the like.

An object of the invention is to provide a door closing mechanism of the character described which will positively close and seal a door or other closure in an opening and at the same time enable a quick and ready operation of the mechanism to enable the opening of the door or closure.

Another object of the invention is to provide a closing mechanism of the character above which utilizes a plurality of locking dogs or the like which are placed under great pressure in their locked position and which are actuated by a manually operative leverage mechanism providing a progressive increase of mechanical advantage of force transmission to the dogs towards the end of their locking movement, so as to minimize the required force to be exerted by the operator of the mechanism.

A further object of the invention is to provide a door closing mechanism of the character described which may be constructed directly on a door or the like and which will be of relatively light weight and of a design enabling a compact arrangement of the mechanism on the door.

Still another object of the invention is to provide a door closing mechanism of the character above which, although as aforementioned, will apply a great closing and sealing force to the door and door frame, is so mounted and constructed on the door as to reduce to a minimum all strain adjacent the center of the door whereby substantially all distortion of the door is eliminated.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawing and description may be adopted within the scope of the invention as set forth in the claims.

Referring to said drawings:

Figure 1 is a front elevation of a door closing mechanism constructed in accordance with the present invention and shown operatively positioned upon a door and door frame therefor.

Figure 2 is an enlarged cross-sectional view of

a part of the door closing mechanism and is taken substantially on the plane of line 2—2 of Figure 1.

Figure 3 is a cross-sectional view similar to Figure 2 and showing part of the mechanism in elevation and illustrating the mechanism in a different position than illustrated in Figure 2.

Figure 4 is a front elevation of the mechanism illustrated in Figures 2 and 3.

Figure 5 is a cross-sectional view of a part of the mechanism illustrated in Figures 2, 3 and 4 and is taken substantially on the plane of line 5—5 of Figure 4.

Figure 6 is a cross-sectional view of a part of the mechanism taken substantially on the plane of line 6—6 of Figure 1.

Figure 7 is a cross-sectional view of a part of the mechanism taken substantially on the plane of line 7—7 of Figure 1.

The closure actuating and locking mechanism of the present invention consists in the combination with a door member and a door frame member therefor, of a plurality of dogs or locking elements carried by one of the members and movable into an engaged position with the other member to hold the members in tightly closed, sealed and locked position, and manual operating means which is connected to the dogs through the medium of a variable leverage mechanism which is operative to progressively increase the mechanical advantage of force transmission between the manual means and the dogs in the course of movement thereof to a locked position, whereby the applied operating force is minimized towards the end of the locking movement.

Referring more specifically to the accompanying drawings, the closure actuating mechanism of the present invention as illustrated in conjunction with a door 8, here shown of a more or less standard ship door type, which is enclosed by and adapted to forcibly bear against a door frame 9. As will be best seen from Figures 2, 3 and 6, the door 8 is provided around its periphery 11 with a channel 12 in which is mounted a gasket 13 which is adapted to forcibly bear against the exposed edge 14 of a flange 16 carried by the door frame 9. Preferably, a reinforcing flange 17 is mounted around the periphery 11 to define the channel 12 and to reinforce the door structure and the opposed walls of the channel may be tapered outwardly of the channel so as to securely hold the gasket 13 within the channel.

Means for holding the door securely pressed against the frame here include a plurality of

dogs or locking members 18, 19, 21, 22, 23, 24, 26, 27, 28 and 29 which as here shown, are pivotally carried by the door adjacent the periphery thereof and which are adapted to move outwardly and against the door frame so as to draw the gasket into tightly pressed engagement with the leading edge 14 of the flange 16. Each of these dogs or locking members are here shown of similar construction and an explanation of one will suffice for all. Each of the dogs is composed of a pair of spaced plates 31 and 32 which are rigidly secured together in spaced relation by means of a rib 33 and which are each fixed at one end thereof to a shaft 34. The shaft 34 is secured adjacent to the front panel of the door 8 and the flange 17 by means of a bearing block 36 which is adjustably supported on the flange 17 by means of screws 37 and 38 threaded through bosses 39 and 41 formed on the flange. The lower ends 42 of the screws are seated in recesses 43 formed in the bearing block, whereby the spacing of the latter from the front panel of the door may be accurately controlled. The plates 31 and 32 are here shown of a form similar to bell cranks and extend transversely from the plane of the door beyond the plane of the frame and then at substantially right angles to overly the frame and to bear forcibly against the same in the locked position of the dogs. The engagement of the dogs and frame is here effected by means of a pair of spaced rollers 44 and 46 which are carried at the outer ends 47 and 48 of the members 31 and 32 by means of a pin 49 passing through such ends and the rollers. Preferably, the frame is reinforced at its point of engagement with the rollers and as here shown, a bar 51 is provided on the frame in abutting relation to the flange 16 and at the inner side of the frame to support the rollers 44 and 46.

In accordance with the present invention, the locking dogs are arranged to be manually displaced from an open inoperative position, as illustrated in Figure 3, wherein the rollers 44 and 46 are withdrawn to within the periphery of the door, to an outwardly rotated position such as shown in Figure 2, wherein the rollers are forcibly drawn against the frame to seal the door in closed position. The present mechanism has been particularly designed for use with closures requiring a great closing force to hold the same in sealed position in the door frame. It is customary in the case of ship doors to sink the knife edge or flange on the frame into a gasket on the door as here provided, to a depth of approximately one-eighth of an inch, and with the use of ordinary rubber gaskets this operation requires the application of a force of upwardly of one hundred and fifty pounds at each dog. A principal object of the present invention and as above mentioned, is to provide a door closure mechanism of this character which may be quickly and easily operated by manual operation so as to enable a fast and immediate opening of the door in case of emergency. To accomplish this result, I provide an actuating mechanism for the dogs which will provide for a relatively fast movement of the dogs from their open position, as shown in Figure 3, to adjacent their closed position, as shown in Figure 2, and thereafter a relatively slow movement of the dogs to a fully locked position by progressively increasing the mechanical advantage of force transmission as the dogs are moved from open to closed position, whereby the final locking movement of the dogs may be effected with a minimum applied oper-

ating force. In this manner the required applied force for initially moving the dogs from open to closed position is accompanied by a small mechanical advantage, sufficient only to overcome the normal frictional resistance and inertia to movement, whereas the final locking movement of the dogs is accompanied with a great mechanical advantage whereby the actual movement of the knife edge into the gasket under great force is effected with a minimum applied force to the manual operating means.

In carrying out the above method of application, I embody in part of the actuating mechanism a toggle mechanism, and an associated link structure which is operative to change the mechanical advantage of force transmission during the course of movement of the dogs 21, 22, 23, 27, 28 and 29. As here shown there is mounted on the door, toggle links 52, 53, 54, 56, 57 and 58 which are in each instance secured at their outer ends 59 to a clevis 61 in turn pivotally secured to a link 62 which is journaled on the pin 49 between the rollers 44 and 46. As will be seen from Figure 1, the arrangement of the dogs on the door is such as to position dogs 21 and 29, dogs 22 and 28, and dogs 23 and 27, at opposite sides of the door so that dogs 21 and 29 are substantially horizontally aligned, as are also dogs 22 and 28, and dogs 23 and 27. The inner end 63 of link 52 is pivoted to the inner end 64 of link 58 adjacent the vertical center of the door, as is also the case with the inner end 66 of link 53 and the inner end 67 of link 57, and the inner end 68 of link 54, and the inner end 69 of link 56. The construction of such pivotal connection is illustrated in Figures 2 and 4 in connection with links 52 and 58, which is typical of the pivotal connection of the other pairs of links above mentioned. As here shown, the inner end 64 of link 58 is secured to a clevis 71, which is in turn engaged in a larger clevis 72 attached to the inner end 63 of link 52. The clevises 71 and 72 are pivotally secured together by means of a pin 73 which passes outwardly through these members in a direction normal to the plane of the door and at the inner end thereof is provided with a roller 74, which is carried in a channel 76 extending along the vertical center portion of the door. In this manner the inner pivoted ends of the links are restricted in their movement to a guided vertically central position on the door and the center pivotal connection of each pair of links forms the knee of a toggle joint.

The operation of the mechanism for opening and closing the dogs, as will now be understood, consists in displacing the knee of each of the toggle joints vertically along the door frame so as to move the opposing toggle links, such as 52 and 58, into and out of an aligned position. The links, as will be clear, are in such aligned position in locked position of the dogs, and are so illustrated in Figure 1. To move the dogs to open position the links are here displaced away from an aligned position, as indicated in dotted lines in Figure 1, so as to draw the outer ends of the links inwardly towards the center of the door. In the case of links 52 and 58, and 53 and 57, the central pivot is drawn downwardly to open the dogs, whereas in the case of links 54 and 56 the center pivot is raised in opening the dogs. This is here effected by mounting on the door intermediate the links 53-57 and links 54-56 at a central position widthwise of the door, a rotary crank 77 which is connected by a link 78 to the center

pivot of links 53 and 51 and which is connected at an opposite side of its pivotal axis by link 78 to the central pivot of links 54 and 56. The center pivot of links 53 and 51 is in turn connected to the center pivot of a connecting bar 81. 5

The construction of the rotary crank 17 and the associated mechanism is best seen in Figures 1 and 7. As here shown, the crank is in the form of a pair of spaced plates 82 secured at the inner side of the door on a pin 83 extending 10 through the door to the outer side thereof. Also secured to the pin adjacent the plates 82 and fixed thereto, as here shown, by means of a nut 84, is a manually engageable lever 86. Preferably, the connection of the lever to the pin as 15 well as the plates to the pin, is effected in a non-circular interfit, so as to hold these members against relative rotation. The pin is here shown journaled in bearing members 87 and 88 mounted at opposite sides of the door in a bushing 89 secured to the door. A packing 91 is preferably mounted between the adjacent inner ends of the bearings. A lever 92 is preferably provided at the outer side of the door and as here shown is secured to the outer end 93 of the pin and held 20 in place by means of a nut 94 threaded on the pin. 25

The door here illustrated is as aforementioned, a more or less standard form of ship door and is formed with rounded or curved corners at which are located in the present instance the dogs 18, 19, 24 and 26. These dogs are connected with links 96, 97, 98 and 99 which are in each instance secured to the pin 49 of the dogs in the manner above described and which are operatively connected at their opposite ends to links 101, 102, 103 and 104. The opposite ends of the last mentioned links are pivoted to reinforcing members 106, 107, 108 and 109 set on the inside panel of the door. In the closed position of dogs 18, 19, 24 and 26 the aforementioned links attached to these dogs are in substantially aligned position and these dogs are moved to an open position by swinging such links out of their aligned position. The center pivotal connection of the sets of links 96—101, 97—102, 98—103, and 99—104, in each instance forms the knee of a toggle joint and the knees of these joints are connected by a series of links 111, 112, 113 and 114. Links 111 and 112 are pivoted together at their inner ends and secured in the center guide channel 76 and connected to the knee of links 52 and 58 by means of a bar 116. Similarly, the inner ends of links 113 and 114 are pivoted together and secured in the channel 76 and connected to the knee of links 54 and 56 by means of a bar 117. 35

In operation of the device, the lever 86 is moved in a counter-clockwise direction, as viewed in Figure 1, to open the dogs and in a clockwise direction to close the dogs, the entire movement of the handle being approximately 135° of arc. Upon movement of the handle 86 in a clockwise direction from the locked position, as illustrated in Figure 1, the knees of the several toggle links are drawn towards the axis of the lever, as 60 illustrated in dotted lines in Figure 1, whereby the dogs are drawn away from the door frame. Upon movement of the handle from open to closed position, the knees of the several toggle joints are moved towards an aligned position of the toggle links, and as will be understood, as the toggle links approach an aligned position, the mechanical advantage of force transmission increases so that at the end of the stroke such 65 mechanical advantage reaches a large magni- 70 75

tude (theoretically infinity). It will be further seen with reference to Figures 2 and 3 that the dogs swing between their open and locked positions adjacent the top of their arcuate movement where the horizontal component of such movement, as represented by the movement of the link 58 is much greater than the component of movement at right angles thereto, represented by the movement between the door and frame, whereby a substantial gain in mechanical advantage is obtained. In other words after initial engagement of the roller 44 with the bearing bar 51 in the locking movement of the dog, the roller moves horizontally across the bar 51 a greater distance than the door moves in the direction of the bar whereby the applied force in the link 58 is multiplied several times at the bar 51.

Preferably, each of the toggle links is provided at its opposite end with left and right-hand threads, so that each of the dogs may be manually adjusted to increase or decrease its amount of movement. Also, the adjustable construction of the bearing blocks 36 as above described, enables an adjustment of the rollers 46 relative to the door frame, so as to take up for wear and compression of the gasket. Further, by reason of the construction of the mechanism and particularly the securing of the dogs exclusively adjacent the periphery of the door, and the movement of the toggle links into a substantially aligned position into the closed locked position of the dogs, the entire stress set up by the closing force is carried around the periphery of the door and substantially no stress whatever created over the central portion of the door, whereby distortion of the door is avoided. 30 35

It will now be understood that the mechanism of the present invention is capable of applying a very great closing force to a door sufficient to positively seal the door in its enclosing frame, and yet the mechanism itself is relatively simple and compact in form and light in weight and capable of being easily and readily operated by a relatively short and easy throw of the operating member. 40 45

I claim:

1. In combination with a door and door frame therefor, a pair of members pivoted to said door adjacent opposite edges thereof, each of said members being pivoted along an axis substantially parallel to the plane of the door and movable in an arc normal to said plane to engage said door frame, links pivoted to said members along axes normal to said plane and pivoted together at a central portion of the door to form a toggle knee thereat, a track carried by said door at a central portion thereof and extending substantially parallel to the axis of said members, and manual operating means slidably carried in said track and engaging said knee for displacing the latter into a substantially aligned position of said links. 50

2. In combination with a door and door frame therefor, a pair of members pivoted to said door adjacent opposite edges thereof, each of said members being pivoted along an axis substantially parallel to the plane of the door and movable in an arc normal to said plane to engage said door frame, links pivoted to said members along axes normal to said plane and pivoted together at a central portion of the door to form a toggle knee thereat, a track carried by said door at a central portion thereof and extending substantially parallel to the axis of said members, a rotary manual operating means carried by said 70 75

door, and a link pivoted at one end to said means and at an opposite end to said knee, said last named link end being slidably carried in said track for displacing said knee into a substantially aligned position of said first mentioned links.

3. In combination with a door and an abutting door frame, a door closing and locking member pivotally mounted on said door adjacent one edge thereof and having a pivotal axis substantially parallel to the plane of the door and movable in an arc normal to said plane to engage said door frame to hold said door in closed position thereagainst, manually operated means carried by said door and connected to said member for displacing the latter to and from said frame, and means for adjusting the spacing between the pivotal axis of said member and said door.

4. In combination with a closure and abutting closure frame, a plurality of members pivoted to said closure adjacent opposite edges thereof along parallel axes substantially parallel to the plane of the closure and rotatable in a common plane perpendicular to the plane of the closure from a retracted position spaced from the frame to an extended position engaged with the frame for holding the closure thereagainst, a member mounted substantially centrally of the closure and movable substantially parallel to the plane of the closure and along a line parallel to said pivotal axes at right angles to the plane of movement of said first members, toggle links pivoted at one end to said second member and at their opposite ends to said first members and movable with said second member into and from an aligned position of said links to cause an extension and retraction of said first members, an operating lever pivoted to the closure along an axis substantially perpendicular to the plane of the closure and having a length which is entirely confined within the area of the closure, and means connecting said lever and said second member providing a full movement of said second member and a full movement of said first members between the extended and contracted positions thereof aforesaid upon a rotation of said lever less than a complete revolution thereof.

5. In a door adapted for mounting in a frame opening for movement to and from a closed position, a reinforcing flange extending around the door adjacent the periphery thereof and within said opening and extending from the door at substantially right angles to the plane of the door, a plurality of locking members pivotally supported on the door at said flange and each comprising a pair of spaced, longitudinally curved strips, a reinforcing rib joining said strips in spaced parallel relation, a shaft secured to one end of each of said strips, bearing means carried by said flange and supporting said shaft on an axis parallel to the plane of the door for movement of each member in an arc in a plane normal to the plane of the door between a retracted position of the member spaced from the frame and an extended position of the member engaged with the frame for holding the door in closed position.

6. In a door adapted for mounting in a frame opening for movement to and from a closed position, a reinforcing flange extending around the door adjacent the periphery thereof and within said opening and extending from the door at substantially right angles to the plane of the door, a plurality of locking members pivotally supported on the door at said flange and each comprising a pair of spaced longitudinally curved strips, a

shaft secured to one end of said strips, bearing means carried by said flange supporting said shaft on an axis parallel to the plane of the door for movement of each member in an arc in a plane normal to the plane of the door for movement to and from an engaged position with said frame, a pin connecting the opposite ends of said strips, a pair of rollers carried by said pin adjacent said strips, and a connection member mounted on said pin intermediate said rollers.

7. In a door adapted for mounting in a frame opening for movement to and from a closed position, a reinforcing flange extending around the door adjacent the periphery thereof and within said opening and extending from the door at substantially right angles to the plane of the door, a plurality of locking members pivotally supported on the door at said flange and each comprising a pair of spaced longitudinally curved strips, a shaft secured to one end of each of said strips, bearing means carried by said flange and supporting said shaft on an axis parallel to the plane of the door for movement of each member in an arc in a plane normal to the plane of the door between a retracted position of the member spaced from the frame and an extended position of the member engaged with the frame for holding the door in closed position, toggle means operating between opposed members at opposite sides of the door for displacing said members between said positions, and set-screw means for adjusting the position of said bearing means to regulate the pressure of said members against said frame.

8. A closing and locking mechanism for a door and frame therefor comprising, a plurality of members pivoted at one end thereof to said door at opposite sides of said door along parallel axes parallel to the plane of the door and movable in arcs perpendicular to the plane of said door so as to swing the opposite outer ends of said members to and from said frame for holding said door in closed position against said frame, rollers carried by said outer ends of said members for engagement with said frame, the spacing between said rollers and the pivotal axes of said members and the location of said axes relative to said frame being such as to cause said rollers to roll over and to bear forcibly against said frame sides in the closed position of the door to draw said door and frame together, and manually operated means for swinging said members about their pivotal axes as aforesaid.

9. A closing and locking mechanism for a door and frame therefor comprising, a plurality of members pivoted at one end thereof to said door at opposite sides of said door along parallel axes parallel to the plane of the door and movable in arcs in a common plane perpendicular to the plane of said door so as to swing the opposite outer ends of said members to and from said frame for holding said door in closed position against said frame, rollers carried by said outer ends of said members for engagement with said frame, the spacing between said rollers and the pivotal axes of said members and the location of said axes relative to said frame being such as to cause said rollers to roll over and to bear forcibly against said frame sides in the closed position of the door to draw said door and frame together, toggle links extending across said door and pivoted at their outer ends to said members adjacent the outer ends thereof whereby the thrust of said links is applied substantially at the axes of said rollers, the inner ends of said toggle links

being pivoted together adjacent the center of the door, and manually operative means connected to the inner pivoted ends of said toggle links for moving said links into and from an aligned position thereby causing said members to swing about their axes as aforesaid.

10. A closing and locking mechanism for a door and frame therefor comprising, a plurality of members pivoted at one end thereof to said door at opposite sides of said door along parallel axes parallel to the plane of the door and movable in arcs in a common plane perpendicular to the plane of said door so as to swing the opposite outer ends of said members to and from said frame for holding said door in closed position against said frame, rollers carried by said outer ends of said members for engagement with said frame, the spacing between said rollers and the pivotal axes of said members and the location of said axes relative to said frame being such as to cause said rollers to roll over and to bear forcibly against said frame sides in the closed position of the door to draw said door and frame together, toggle links extending across said door and pivoted at their outer ends to said members adjacent the outer ends thereof whereby the thrust of said links is applied substantially at the axes of said rollers, the inner ends of said toggle links being pivoted together adjacent the center of the door, and means for displacing the inner pivoted ends of said links into and from an aligned position to cause a swinging of said members as aforesaid and including a manually operated lever mounted on said door and movement transmission means connecting said lever with said link ends providing a relatively small mechanical advantage whereby the operative displacement of said links may be effected by a relatively short movement of said lever.

11. A closing and locking mechanism for a door and frame therefor comprising, a plurality of members pivoted at one end thereof to said door at opposite sides of said door along parallel axes parallel to the plane of the door and movable in arcs in a common plane perpendicular to the plane of said door so as to swing the opposite outer ends of said members to and from said frame for holding said door in closed position against said frame, rollers carried by said outer ends of said members for engagement with said frame, the spacing between said rollers and the

5 pivotal axes of said members and the location of said axes relative to said frame being such as to cause said rollers to engage and to roll over and to bear forcibly against said frame in the closed position of the door adjacent the top of the swinging arc of said members to thereby draw said door and frame together with a degree of movement therebetween less than the component of movement of said members parallel to the plane of said door, and manually operated means connected to said members adjacent said outer ends thereof for swinging said members as aforesaid and applying an operating force to said members in the locking positions thereof substantially parallel to the plane of said door.

10 12. A closing and locking mechanism for a door and frame therefor comprising, a plurality of members pivoted at one end thereof to said door at opposite sides of said door along parallel axes parallel to the plane of the door and movable in arcs in a common plane perpendicular to the plane of said door so as to swing the opposite outer ends of said members to and from said frame for holding said door in closed position against said frame, rollers carried by said outer ends of said members for engagement with said frame, the spacing between said rollers and the pivotal axes of said members and the location of said axes relative to said frame being such as to cause said rollers to engage and to roll over and to bear forcibly against said frame in the closed position of the door adjacent the top of the swinging arc of said members to thereby draw said door and frame together with a degree of movement therebetween less than the component of movement of said members parallel to the plane of said door, and manually operated means connected to said members adjacent said outer ends thereof for swinging said members as aforesaid and applying an operating force to said members in the locking positions thereof substantially parallel to the plane of said door.

20 25 30 35 40 45 50

CHARLES E. ARTHUR.
